STROLLER

Roy P. Friddell, Galveston, Tex.

Application December 18, 1953, Serial No. 28,129

Term of patent 14 years

(Cl. D14—14)

Fig. 4

To all whom it may concern:

Be it known that I, Roy P. Friddell, a citizen of the United States of America, residing at Galveston, Galveston County, State of Texas, have invented a new, original, and ornamental Design for a Stroller, of which the following is a specification, reference being made to the accompanying drawings, forming a part hereof.

Fig. 1 is a side view of a stroller embodying my new design;

Fig. 2 is a front view;

Fig. 3 is a rear view;

Fig. 4 is a top view; and

Fig. 5 is a bottom view.

1 claim:

The ornamental design for a stroller, substantially as shown.
